John O. Grady
ATTORNEY

UNITED STATES PATENT OFFICE

HARRY J. LEBHERZ, OF FREDERICK, MARYLAND, ASSIGNEE TO THE EVEREDY COMPANY, OF FREDERICK, MARYLAND, A CORPORATION OF MARYLAND

BOTTLE CAPPER

Application filed September 5, 1930. Serial No. 480,008.

My invention relates broadly to bottle capping tools and more particularly to a bottle capper having means for adjusting the capping ram for operation upon bottles of different sizes.

One of the objects of my invention is to provide a construction of bottle capping tool employing a ram adapted to be pressed downwardly upon a bottle for applying a crown cap thereto with means for regulating the operative position of the ram with respect to a bottle.

Another object of my invention is to provide a construction of gear adapted to be moved into or out of mesh with the ram of a bottle capping tool for enabling the ram to be adjusted to selected positions for operation upon bottles of different sizes.

A further object of my invention is to provide a construction of slide gear for bottle capping tools having a pair of limiting abutments and rack teeth cut therein for regulating the position and limiting the movement of the ram in a bottle capping tool.

Other and further objects of my invention reside in the construction of actuating gear for a bottle capping tool as set forth more fully in the specification hereinafter following by reference to the accompanying drawing, in which:

Figure 1 shows a side elevation of the bottle capping tool of my invention; Fig. 2 is a front elevation of the bottle capping tool of my invention showing the actuating gear in engaged relation with respect to the ram; Fig. 3 is a view of the bottle capper with the actuating gear disengaged from the ram to enable the ram to be adjusted for operation of the capper on different sized bottles; Fig. 4 is a fragmentary cross-sectional view of the ram and actuating gear taken on line 4-4 of Fig. 5; Fig. 5 is a cross-sectional view of the ram and actuating gear taken on line 5-5 of Fig. 4; Fig. 6 is a cross-sectional view of the ram and actuating gear with the actuating gear shifted to disengaged position, the view being taken on line 6-6 of Fig. 7; Fig. 7 is a horizontal sectional view taken on line 7-7 of Fig. 6 showing the actuating gear shifted out of engagement with the ram in a position

by which the ram may be vertically adjusted; and Fig. 8 is a perspective view showing the actuating gear employed for adjusting the ram in the bottle capper of my invention.

In my copending application Serial No. 55 399,259, filed October 12, 1929, I have described a rack type of bottle capper which I have described as a gear top capper. My present invention relates to an improved form of actuating gear for a capper of the general 60 construction set forth in the aforesaid application by which the capping ram may be readily adjusted to a selected position to facilitate the applying of crown caps to bottles of different sizes.

I provide an elongated shaft member 65 adapted to extend horizontally through the head of the bottle capping tool normal to the axis of the ram. The elongated shaft member is provided with longitudinally extending teeth throughout a portion of its length 70 adapted to mesh with the teeth formed on the ram. When the laterally extending shaft member is shifted sidewise the teeth thereon are disengaged from the teeth on the rack 75 enabling the rack to be adjusted freely through the head of the bottle capping tool to a position conforming to the size of the bottle which is being capped. When the laterally extending shaft is restored to normal position 80 the teeth thereon engage the teeth on the rack permitting the bottle capping tool to be successively operated. The actuating shaft is provided with opposed limiting stops 85 providing abutments which limit the stroke of the actuating lever. In the bottle capping tool of my present invention it is unnecessary to remove the actuating parts as was the case in the construction of my application aforesaid for effecting an adjustment of the capping 90 ram for the lateral shift actuating gear is sufficient to permit the required adjustment of the position of the capping ram.

Referring to the drawing in more detail, 95 the bottle capping tool is shown as comprising the cast frame 1 having base 2 and head 3. The head 3 is drilled as shown at 25 to receive the ram 17 having integrally connected rack teeth 18 cut on one side thereof. The head of the bottle capper is provided with a 100

laterally extending portion 5 adjacent the vertically extending head 3. The portion 5 is drilled from the right side thereof toward the left side thereof as represented at 4. The 5 left wall of the drilled portion 5 is apertured as represented at 26 to receive the elongated laterally projecting shaft 7 which is moved laterally through the rearwardly extending portion 5 in assembling the bottle capping 10 tool. The laterally extending shaft 7 has an enlarged end 6 thereon through which the actuating lever 15 passes. The laterally extending portion of shaft 7 is grooved for providing teeth 20 thereon as shown more clearly in Fig. 8.

Two annularly disposed abutments are provided on the shaft 7 as represented at 20a and 20b which function as illustrated more clearly in Fig. 4 as limiting stops for 20 the angular throw of the actuating lever 15. A collar 10 is telescopically disposed over the shaft 6 and is provided with a notch 27 therein which engages the projecting end of the angularly disposed actuating lever 15 thus locking the same against casual rotation. One side of the collar 10 terminates in a hook 11 which is engaged by coil spring 12 anchored at 14 on the frame 1. The spring 12 tends to retain the hook 11 in the position illustrated in Fig. 1 under spring tension. As the lever 15 is revolved in a counter-clockwise direction for effecting a bottle capping operation the spring 12 exerts tension on hook 11 for restoring the actuating lever to elevated position after each capping operation. The laterally extending shaft 7 has an annular groove 8 formed in the end thereof which is adapted to be engaged by washer 9 after the actuating shaft has been assembled through the aperture 26 in the rearwardly extending portion 5 of the bottle capper. The washer 9 thereafter serves as an abutment against the accidental removal of the laterally extending shaft 7 when the gear teeth 20 are disengaged from the teeth 18 on the ram 17. The ram 17 carries a bottle capping throat 19 thereon for applying a crown cap to a bottle as represented for example at 28 in Fig. 1. 50 The actuating lever 15 is provided with a hand grip 16 for effecting movement of the actuating lever in performing each bottle capping operation.

In the operation of the bottle capping tool 55 the laterally extending shaft 7 is shifted toward the right as shown in Fig. 7 to disengage the teeth 20 from the rack teeth 18. The rack 17 is then free to be vertically adjusted as may be desired. When it is desired to 60 maintain the ram in a predetermined position the laterally extending shaft 7 is shifted toward the left thereby effecting an engagement between teeth 20 and teeth 18 as shown in Fig. 5. The upper and lower limits of 65 movement of shaft 7 is determined by the

abutment of portions 20a and 20b with the rack teeth 18.

The spring 12 is so arranged with respect to the frame 1 and actuating gear 20 that a constant force tending to maintain the gear 20 in engagement with the teeth 18 on rack 17 is exerted. That is, when the actuating gear is shifted to disengage the teeth 20 from the rack teeth 18, the spring 12 operates to restore the actuating gear to engagement with the rack at the same time that the spring tends to elevate the lever 15 into bottle capping operation.

The bottle capper construction of my invention has been found to be extremely practical and successful in its operation and while I have described my invention in one of its preferred embodiments I desire that it be understood that modifications may be made and that no limitations are intended other than are imposed by the scope of the appended claims.

What I claim as new and desire to secure by Letters Patent of the United States is as follows:

1. A bottle capping tool comprising a frame terminating in a vertically positioned head, a ram movable through the head of said frame, a bottle capping throat carried by said ram said head having a rearwardly extending portion comprising a hollow cylindrical member open at one end thereof and apertured at the opposite end thereof, an actuating gear including a shaft member projectable through the open end of said rearwardly extending portion and through the apertured end of said rearwardly extending portion, teeth extending throughout a portion of the length of said shaft member and engageable with teeth formed on said ram when said actuating gear is shifted to a limiting position through the cylindrical rearwardly extending portion of said head, a collar member carried by said shaft member, a tongue extending from said collar member and a coil spring connected between said tongue and a point on said frame, said spring tending to exert axial tension on said shaft member for maintaining the teeth on said shaft member in engagement with the teeth on said ram while continuously urging said ram in an extreme upper position preparatory to a bottle capping operation.

2. A bottle capping tool comprising a frame structure terminating in a vertically disposed head, a ram movable through said head, a bottle capping throat carried by said ram for applying a crown cap to a bottle, said frame having a rearwardly extending portion integrally connected with said head, a shift gear projecting laterally through said rearwardly extending portion, said shift gear having teeth extending throughout a portion of its length adapted to engage teeth formed on said ram, the teeth on said actuating gear

- being laterally shiftable out of engagement with the teeth on said ram for effecting adjustment in the position of said ram, said actuating gear having opposite limiting stops formed integral therewith for limiting the stroke of said ram when said actuating gear is subjected to angular movement in engagement with the teeth on said ram, a member connected with said actuating gear, and spring means connected between said frame structure and said member for normally maintaining said actuating gear in engagement with said ram and elevating said ram in bottle capping position.
3. A bottle capping tool comprising a frame structure terminating in a vertically disposed head, a ram movable through said head, a bottle capping throat carried by said ram for applying a crown cap to a bottle, a rearwardly extending portion on said frame, a shift gear projecting laterally through said rearwardly extending portion, said shift gear having teeth extending throughout a portion of its length adapted to engage teeth formed on said ram, the teeth on said gear being shiftable out of engagement with the teeth on said ram for effecting a vertical adjustment in the position of said ram, an annular member carried by said shift gear, and spring means extending radially from said annular member to a point on said frame structure for maintaining said gear in mesh with said ram while exerting a continuous torque on said gear for restoring said ram to the extreme upper position of its stroke after each successive capper operation.

In testimony whereof I affix my signature.
HARRY J. LEBHERZ.
